UNION SUIT.

1,092,900.

Specification of Letters Patent. Patented Apr. 14, 1914.

Application filed July 18, 1912. Serial No. 710,171.

To all whom it may concern:

Be it known that we, EDWARD H. DAVISON and MARTIN K. PASCO, citizens of the United States, residing at New Britain, in the county of Hartford and State of Connecticut, have invented certain new and useful Improvements in Union Suits, of which the following is a specification.

Our invention relates to improvements in union suits or combination garments with closed drop-seats, and the object of our improvement is to so construct a union suit which being closed at the seat and crotch, completely covers the body, and by means 15 of its belted feature, retains the drop-seat in proper position without the necessity of buttons at the back.

In the accompanying drawing:—Figure 1 is a rear elevation of our suit as it appears 20 in use. Fig. 2 is an enlarged rear elevation of the middle portion of the same, the belt being unbuttoned at both ends. Fig. 3 is a front elevation of the same, the ends of the belt being buttoned. Fig. 4 is a plan view of 25 the gussets for the seat and crotch. Fig. 5 is a rear elevation on the same scale as Fig. 1, showing the drop seat let down of a modified form of garment to the extent of having an additional button-hole in the waistband 30 at the middle of the top of the drop seat and a button on the body portion to coöperate therewith. Fig. 6 is an enlarged detail view of the button hole side of the front at the waist. Fig. 7 is an enlarged detail 35 view of one end of the belt. Fig. 8 is a detail perspective view of the two layers of the smaller gusset.

Our improvement in the main, is applicable to union suits made in any ordinary 40 manner from either woven or knitted fabric.

As shown, our suit is made from knitted fabric which is first made into an ordinary union suit, without a drop seat. We then 45 cut the back transversely at about the waist line for a width at the waist equal to the width of the desired drop seat at the top, and then cut down on each side as far as the drop is intended to go. This leaves a flap for the drop seat which is a part of the 50 original back and is continuous with the seat and legs. The flap so cut out is then slit down its middle to the crotch and then each leg is slit from the crotch downwardly to a point near the knee. We then insert 55 the two gussets 9 and 10, the upper part 9^a

of the gusset 9 coming to a point at the top where the two sides 12 of the drop seat come together, the wider middle part 9^b being at the seat with the two lower points 9^c extended from the crotch down the legs as far as the legs are slit. The gusset 10 is a small 60 rectangular piece of two thicknesses which are sewed into the crotch, whereby we make the crotch and seat portion very roomy and of great strength. When the gusset 10 is 65 made of fabric we prefer to have the wale in the two layers cross each other as shown in Fig. 8. Whether made of a knit or other fabric, we prefer to have both layers of the gusset 10 placed with the finished side out. 70 A belt 11 is secured to the upper edge of the drop seat or flap by its middle portion while the two ends having button holes 22 are intended to come together at the front where they may be secured to the special button 13 75 which is for convenience set between two of the button holes 14 in the facing 15 at the front. One of the buttons used on the front facing of the suit can also be used for the belt. The button holes may be duplicated 80 to any desired number, three being shown and between these button holes we form double rows 16 of cross-stitching as best shown in Fig. 7. In order to partly fill the space from which the sides 12 of the flap 85 are cut we insert a partial back 17 as shown in Fig. 5. If desired a button hole may be made in the middle of the back at the waist line as shown in Fig. 5 and a button 18 provided at the waist line of the body of the 90 garment to coöperate therewith.

By attaching the belt to the upper edges of the closed drop seat and providing the ends of the belt with button holes at the front, and the facing with a button, the seat 95 may be raised and held in place by the said belt so that no button at the back is necessary, although one may be used if desired. It is necessary to unbutton but one end of the belt in order to let the drop seat or flap 100 down for use, but both ends may be unbuttoned if desired. The extra button holes in the ends of the belt are provided in order to adjust the garment to persons of varying waist measure. When the suit is worn by 105 a person who does not require the use of the end button hole or holes, the double rows of transverse stitching enable the wearer to cut off the surplus between any two rows of stitching and still leave a 110

stitched end on the belt. By means of a gusset double pointed at the bottom and with a single point at the top, we provide ample room at the seat and upper part of the legs 5 and relieve the suit from undue strain at these points. The smaller gusset at the crotch, within the main gusset gives superior strength at what is ordinarily a weak point.

The original ordinary union suit mentioned is made of proper full size at the 10 waist line so that extra provision for fullness is not required precisely at the waist line and therefore the gusset 9, which extends the full depth of the drop seat can 15 be and is made V-shape at the upper end, with the apex at the waist line, at the junction of the two sides 12 of the drop seat. Furthermore, the button-hole at the said junction, as shown in Fig. 5, that engages 20 with the button 18, serves virtually to connect the upper end of the gusset 9 with the body portion of the garment, as distinguished from the sides 12, and thereby 25 serves to connect the said apex with the said body portion of the garment.

We claim as our invention:—

1. A union suit comprising a garment

body having a full and complete waist line portion, a drop seat composed of sides whose upper ends fit the said garment body along 30 the said waist line portion, and a gusset inserted between the said sides, and the upper part of the said gusset being V-shape and the apex thereof being connected to the opposed edges of the said upper ends of the 35 drop seat.

2. In a union suit comprising a garment body and a drop seat in the form of a flap having the upper end at the waist line and the said drop seat being provided with a 40 gusset, the said gusset being extended for the entire depth of the said drop seat up to the said waist line and the upper end thereof being V-shape with the apex at the said waist line, the said drop seat having 45 a button-hole adjacent the said apex, and a button being provided at the middle of the said garment body for engaging with the said button-hole.
